UNITED STATES PATENT OFFICE.

PERRY S. MARTIN, OF BROADWAY, VIRGINIA.

INCUBATOR-ALARM.

No. 926,669.

Specification of Letters Patent. Patented June 29, 1909.

Application filed February 17, 1909. Serial No. 478,376.

To all whom it may concern:

Be it known that I, PERRY S. MARTIN, a citizen of the United States, residing at Broadway, in the county of Rockingham and State of Virginia, have invented certain new and useful Improvements in Incubator Alarms, of which the following is a specification.

This invention relates to thermostatic alarms and more particularly to an alarm especially designed for use in connection with incubators for notifying the attendant in case the temperature of the egg receiving compartment rises above or falls below a predetermined degree.

The object of the invention is to provide an alarm including an energized circuit, the terminals of which are connected with a pair of contact members arranged on opposite sides of the damper controlling lever and actuated by the latter to make and break the circuit and thereby sound the alarm.

A further object of the invention is generally to improve this class of devices so as to increase their utility, durability, and efficiency.

For a full understanding of the invention and the merits thereof and also to acquire a knowledge of the details of construction and the means for effecting the result, reference is to be had to the following description and accompanying drawings, in which:

Figure 1 is a side elevation of an incubator constructed in accordance with my invention; Fig. 2 is a detail perspective view of the support carrying the movable contact arms; Fig. 3 is a transverse sectional view through the supporting clip of the contact arms.

Corresponding and like parts are referred to in the following description and indicated in all the views of the drawings by the same reference characters.

The improved thermostatic alarm forming the subject matter of the present invention, is principally designed for attachment to incubators, and by way of illustration is shown in connection with an incubator of the ordinary construction, in which 5 designates the frame, 6 the lamp and 7 the damper controlling lever, which latter is pivotally mounted at 8 and operatively connected to a thermostat 9, of any approved construction.

The device comprises a vertical support 10 preferably secured to the top of the incubator near the lamp 6, and to one side of which is secured a clip 11 having a strip 12 secured

to the upper portion thereof and extending to a binding screw 13. The clip 11 is preferably stamped or otherwise formed of a single sheet of metal bent into substantially T-
shape as best shown in Fig. 3 of the drawings. Pivotaly connected at 14 with the central fin of the clip 11, are spaced arms 15 and 16 constituting contact members, said arms being disposed on opposite sides of the lever 7 and arranged to contact therewith to make and break the circuit, as will be more fully explained hereinafter.

Secured to the support 10 above the clip 11, is an overhanging bracket 17 having its free end formed with spaced perforations for the reception of threaded members or bolts 18 and 19, there being suitable clamping nuts 20 engaging the threaded ends of the bolts 18 and 19 and arranged to bear against the upper surface of the overhanging arm 17 for adjusting the contact arms 15 and 16 toward and from the damper controlling lever. Attention is here called to the fact that the lower arm 16 is slightly longer than the upper arm 15 so as to permit free adjustment of said arms without interfering with each other.

Connected with the binding screws 13 and 21 is an energized circuit including a signal bell 22 and battery 23, there being a switch 24 of any approved type inserted in the circuit between the binding screw 13 and signal 22 so that the alarm can be thrown out of circuit when desired. Connected with the binding screw 21 is the adjacent end of a conductor 24, the opposite end of which is connected with the lever 7 either at its pivot end or at any other suitable point in the length of said lever. Thus it will be seen that should the temperature in the egg receiving compartment rise above a predetermined degree, the thermostat 9 will actuate the lever 7 and move the latter into engagement with one of the contacts 15 or 16 thereby closing the circuit through the battery and conductor 24 and sounding the alarm. Should the temperature fall below a predetermined degree, the lever 7 will be moved in the opposite direction and close the circuit through the other contact arm and also sound the alarm.

By rotating the nuts 20, the contact arms 15 and 16 may be adjusted so as to extend or limit the throw of the lever 7 and thus cause the signal to sound at any desired temperature, the said contact arms being locked in adjusted position by engagement of the nuts.

20 with the adjacent face of the overhanging arm 17, as before stated.

Having thus described the invention, what is claimed as new is:

- 5 1. The combination with an incubator having a damper controlling lever, of an energized circuit including an alarm, spaced contacts disposed on opposite sides of the controlling lever and connected to the terminals of the energized circuit, a bracket, and means operatively connected with the contact arms and extending through the bracket for adjusting said contact arms with respect to the controlling lever.
- 10 2. The combination with an incubator having a damper controlling lever, of a support secured to the incubator, spaced contact arms pivotally mounted on the support and disposed on opposite sides of said lever, an energized circuit connected with the arms, an overhanging bracket secured to the support and having spaced perforations formed therein, threaded bolts pivotally connected with the arms and extending through the perforations in the overhanging bracket, and nuts engaging the threaded rods and bearing against the adjacent face of the bracket for
- 15
- 20
- 25

adjusting the arms laterally with respect to the damper controlling lever.

3. The combination of an incubator having a damper controlling lever, a support secured to the incubator, a clip carried by the support, spaced contact arms pivotally mounted on the clip, binding screws secured to the support, an energized circuit connected with the binding screws and including an alarm, a conductor connecting one of the binding screws with the clip, a second conductor forming a connection between the other binding screw and the damper controlling lever, a bracket carried by the support, threaded rods extending through the bracket and operatively connected with the contact arms for adjusting the arms laterally with respect to the said lever, and nuts engaging the threaded ends of the rods and bearing against the bracket.

In testimony whereof I affix my signature in presence of two witnesses.

PERRY S. MARTIN. [I. S.]
